ASSIGNORS, BY DIRECT AND MESNE ASSIGNMENTS, TO JAMES C. McGlashan
AND EDWARD M. SCRACE, BOTH OF LOS ANGELES, CALIFORNIA.

FLOOR-FURNACE.

1,259,985.

Specification of Letters Patent. Patented Mar. 19, 1918.

Application filed June 15, 1916. Serial No. 103,748.

To all whom it may concern:

Be it known that we, WILLIAM W. HOLMES and JOSEPH N. HAWLEY, citizens of the United States, residing at Los Angeles, in the county of Los Angeles and State of California, have invented certain new and useful Improvements in Floor-Furnaces, of which the following is a specification.

This invention relates to improvements in floor furnaces and has particular relation to floor furnaces of the type in which the combustion chamber is vented, whereby all the products of combustion pass out of a smoke flue and do not enter the house through the register, the air to be heated being taken from the room and passed through and about a heating means, after which it is returned to the room.

It is an object of the invention to provide a device of this character in which the heating member or drum is entirely inclosed within outer and inner walls and in which the burner and the mixer supplying air thereto are incased within parts of the furnace whereby elements of danger from this source are entirely obviated.

It is also a further object of the invention to provide a floor furnace with a centrally mounted heating drum or casing having an air heating central passage way therein, increasing in width from the bottom upwardly whereby the expansion of the air as it is heated tends to produce an upward draft through the furnace.

It is a further object of the invention to provide a furnace of this character in which the burner thereof is mounted in the lower enlarged portion of the combustion chamber formed in the heating drum, the products of combustion being directed upwardly and around all sides of the central heating flue with the exception of a small portion thereof on one side, a baffle device being employed which thus directs the products of combustion, permitting the same to reach the outlet or smoke flue only after being thoroughly distributed about said heat flue, the said baffle also preventing the reheating of the said products of combustion as they are about to pass out through the said smoke flue.

With these and other objects in view the

invention comprises certain novel constructions, combinations and arrangements of parts as will be hereinafter more fully described and claimed.

In the accompanying drawing:

Figure 1 is a vertical longitudinal sectional view taken through a furnace constructed in accordance with this invention.

Fig. 2 is a transverse horizontal sectional view taken upon the line 2—2 of Fig. 1.

Fig. 3 is a detail perspective view of the baffle device employed within the combustion chamber of the furnace.

The furnace of the present invention is designed to afford a device of this character which, while being economical in construction will meet all the ordinary requirements usual in ordinances enacted for the protection of communities from fire and the like and also which will thoroughly vent the device whereby none of the noxious fumes due to the combustion of gas or like fuels, will be permitted to enter the house or dwelling to be heated. The furnace is of the type designed to be mounted in an opening formed in the floor of a room of a dwelling and usually provided with a register or open work top plate as 3. Depending from the register is an outer casing 4 substantially closed at the sides and bottom but open at the top save for the register 3. Within the said casing and suitably spaced therefrom is an inner casing 5 depending from the register 3 and open at the top and bottom. An air passage is thus afforded between the casings for the entrance of air taken from the floor in the room. The inner casing 5 is shorter than the outer casing 4 whereby the air entering between said casings may pass into the bottom of the inner casing and upwardly within and around a heating drum 6 which is spaced within the said inner casing. The said inner drum is formed with cross bars 7 secured to its ends at the bottom of the drum, and adapted to project beyond the sides thereof a suitable distance to rest upon supporting bars 8 which extend laterally of the casing 5 and which are bolted or riveted to the walls thereof near the lower end of the casing. The inner or heating drum 6 is thus supported centrally within the inner casing 5

and reaches nearly to the bottom of said inner casing and also to within a suitable distance of the register or grid 3 at the top. The construction of the heating drum 5 or furnace proper is important since it secures a quick heating of the device and of the air passed through and around it and at the same time utilizes a large proportion of the heat units for heating the air without permitting many of said heat units to escape at the outlet or smoke flue. The outer walls of the said drum 6 are preferably vertical insuring a proper passage way between the drum and the inner casing 5, entirely 10 around the heating device. The said drum is usually made narrower than it is in length though of course other shapes and proportions may be employed without departing from the spirit of the invention. In the 15 central portion of the drum a depending heat flue as 9 is mounted, said flue being open at the top and bottom and the top opening 10 is somewhat larger than the bottom opening 11. The said heat flue is thus given an upwardly flaring shape substantially forming an inverted truncated pyramid or cone. This construction also leaves an enlarged space around the lower 20 end of the flue within the drum which space is occupied by a burner 12 of any desired type. The combustion chamber 13 decreases in its dimensions from the bottom toward the top of the drum 6 and the 25 products of combustion thus pass upwardly and around the flaring heat flue 9 in such a manner that the said heat flue may receive a large portion of the heat units developed. The outlet flue 14 of the device enters the drum 6 above the burner 12 upon one side 30 edge of the said drum. A baffle device 15 is mounted within the combustion chamber and is provided with inclined bottom portions 16 which extend over the burner between the end walls of the drum 6 and the 35 adjacent wall of the heat flue 9. These oppositely inclined portions 16 tend to divide the products of combustion and direct them outwardly and thence upwardly around the walls of the heat flue 9. The 40 substantially upright portion 15 of the baffle prevent the products of combustion from reaching the outlet flue 14 until said products have passed upwardly and around upper inclined portions 17 formed upon the 45 baffle and projecting between the side walls of the heat flue 9. The portions 16 which come quite close to the burner are preferably provided upon their under surfaces with a thick asbestos covering 18. The 50 asbestos covering is next to the burner and prevents the escape of heat above the portions 16, to any great degree and tends to keep the products of combustion, which have cooled considerably by the time they 55 reach the outlet flue 14, from becoming re-

heated again. The burner 12 preferably extends entirely around the flue 9 and is provided with a mixer 19 which projects through the end wall of the drum 6. The said mixer also extends within the walls of a small auxiliary casing 20 which is set into the walls of the outer casings 4 and 5 and projects closely to the heating drum 6. A fuel supply pipe 21 extends to the recess within said casing 20 and a valve controlling nozzle 22 delivers the fuel to the said mixer 19 within said casing. The valve 23 which controls the fuel supply is also mounted within said casing and is formed with an upwardly projecting hollow stem 24 adapted to receive the squared end of an operating rod 25. A set screw 26 removably holds the said rod in said hollow stem. The burner is preferably lighted by means of a pilot burner 27 which is supplied with fuel or gas from the pipe 21 by means of a branch pipe 28. A valve 29 controls the fuel supply for said pilot and a hollow stem 30 projects therefrom which is provided with a recess to receive the end of the squared operating rod 31, a set screw 32 being employed to bind it in place. Both of the rods 25 and 31 extend to the top of the furnace and project within a recess 33 formed in the register, so that an ordinary key or handle, not shown, may be applied thereto for controlling the burner or the pilot. The pilot and the burner may be initially lighted through an opening 34 formed in the top of the drum 6, which opening is normally closed by a hinged door 35 which is generally centrally glazed as at 36 for permitting of the inspection of the burner and pilot, to see whether they are properly lighted.

The outlet or smoke flue 14 preferably passes through a thimble 37 mounted in the walls of the casings 4 and 5, as clearly shown in Fig. 1. Air for supporting combustion in the combustion chamber is introduced through a pipe 38 which passes through the walls of said casings 4 and 5 and enters the drum 6 near the bottom thereof.

The structure of the device will be seen to be such that the cooler air from the floor will readily descend the spaces in the furnace between the walls 4 and 5 of the outer casings, and will pass upwardly around the hot walls of the drum 6 and the heating flue 9 receiving the bulk of the heat units from said drum and delivering the air in highly heated condition within the room. The heating of the air within the flaring heat flue 9 will tend to establish a good draft within the furnace by reason of the expanding of the air, after it is heated within the upwardly enlarging heat flue 9. The air for the products of combustion enters through the mixing device 19 and

through the air inlet pipe 38. The products of combustion pass upwardly around the flue 9 within the drum and thence around the side projections 17 of the baffle device 15 and 5 thence downwardly to the outlet of smoke flue 14. The inclined walls of the heat flue 9 not only facilitate the rising of the heated air within the flue, but having some inclination over the jets of the burner are very 10 highly heated thereby. The air which passes upwardly between the walls of the drum 6 and of the inner casing 5 also sweep upwardly the heat units which might tend to escape through the side walls of the furnace. 15 The hot portions of the mechanism are thus kept well within the furnace structure and the outer passage between the walls of the casings 4 and 5 are kept in cool condition by the constant inflow of air from 20 the floor of the room, there being thus practically no danger to the floor and house structure from the heated portions of the furnace. The thimble 37 affords a cool air jacket space around the outlet flue 14, thus 25 preventing the heating of the air entering between the adjacent walls of the casings 4 and 5.

What is claimed is:—

1. A floor furnace having outer and inner inclosing walls spaced to form air inlets, a heat drum supported centrally within the device and having a burner in the bottom thereof, said device having an outlet flue near the lower end thereof, and a baffle 35 device having inclined lower portions presented to the products of combustion and adapted to divide and spread the same within the drum and upwardly and having laterally inclined portions arranged in the 40 spaces between the drum walls for directing the products of combustion upwardly

and entirely around the heated portions of the drum before returning to the outlet flue.

2. A floor furnace having outer walls 45 and an inner heat drum, a burner within said drum, the said drum having an outlet flue arranged a little above the said burner, in one end of the drum, and a baffle device having a partition portion between the outlet and the burner, and provided with a heat excluding material covering the same and presented to the flames from the burner, and upwardly extending baffle portions on said device for further controlling 50 the direction of the products of combustion. 55

3. A floor furnace comprising inclosing walls, a heat drum suspended within the same and having a combustion chamber surrounding a central heat flue, the said 60 combustion chamber having an outlet flue in the lower portion thereof, and a baffle member mounted between the inner and outer walls of the drum and having a part 65 thereof interposed between the furnace and the outlet flue, an asbestos covering upon the under surface of said interposed portions of the baffle member whereby the products of combustion in their substantially cool condition after they pass out of the 70 outlet flue will be protected from the heat of the burner, and means on the baffle device for properly spreading and directing the products of combustion.

In testimony whereof, we have hereunto 75 set our hands, in presence of two witnesses.

WILLIAM W. HOLMES.
JOSEPH N. HAWLEY.
